UNITED STATES PATENT OFFICE.

JOHN W. HOUGH, OF MARION, INDIANA.

OIL AND GAS SEPARATOR.

SPECIFICATION forming part of Letters Patent No. 537,388, dated April 9, 1895.

Application filed February 8, 1895. Serial No. 537,687. (No model.)

To all whom it may concern:

Be it known that I, JOHN W. HOUGH, a citizen of the United States, residing at Marion, in the county of Grant and State of Indiana, 5 have invented certain new and useful Improvements in Oil and Gas Separators; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 This invention relates to certain new and useful improvements in separators designed for use in oil wells, and the special object of my invention is to produce means for separating the gas from the oil and water of a 20 well, the pressure of the gas constantly causing the water and oil in mixture to be forced from a great depth in the ground, to the surface thereof.

A further object of this invention resides 25 in the provision of a sliding valve fixedly held within a tube carried within an outer surrounding tube, the said valve being designed to regulate the flow of water and oil into the inner tube, which carries the water to the 30 surface of the ground, and to be closed or opened by a running screw thread above the surface of the ground. I further provide a valve which is pivoted to a fixed pin held to the walls of the inner sliding tube, and rests 35 when shut on a valve seat of a tube which telescopes within the valve carrying tube and has a flange, which, when the valve is open abuts against the inwardly turned end of the said valve carrying chamber.

40 To these ends and to such others as the invention may pertain, the same consists further in the novel construction, combination and adaptation of the parts as will be herein-after more fully described and then specifically defined in the appended claim.

45 I clearly illustrate my invention in the accompanying drawings, which with the letters of reference marked thereon form a part of this specification, and in which similar letters 50 of reference indicate like parts throughout both views, in which—

Figure 1, is a sectional view longitudinally through the center of the valve and tubes. Fig. 2, is a cross sectional view on the line *x*, *x* of Fig. 1.

55

Reference now being had to the details of the drawings by letter, *A*, designates the metallic gas conveying tube, running the length of the well, within which tube or pipe an inner tube *B* is located and which is to carry 60 the water and oil to the surface of the ground by the pressure of the natural gas at the lower end of the said inner tube.

C is a cylinder, connected to the lower end of the tube *B*, and is made up of two sections 65 having screw thread connection. The upper section *C'* of said cylinder carries the valve *D*, pivoted on the pin *d* which latter is held to the walls of the cylinder in a fixed relation so that the valve may be raised and lowered 70 with the cylinder, and more readily adjust itself to its seat.

E is a tube having a flange *e* and is designed to telescope within the cylinder *C*, and its top to form a seat for the valve when closed. To 75 the lower end of the pipe *E* is fastened by screw thread connection the union *F* having a series of apertures through which the water and oil are allowed to enter.

G is a cap which rests on the bottom of the 80 well and supports the pipe carrying the valve seat.

The valve *D* has a series of recesses *d'* about its circumference through which the water and oil pass into the cylinder, and the lower 85 section of the cylinder has an inturned end which, when the valve is opened to its full extent, abuts against the flange of the valve seat pipe.

There is sufficient space between the inner 90 tube and the outside one to allow the gas to pass up to the surface of the ground where it is carried off through suitable pipes *h*, *h*. The inner tube, which carries the valve in the cylinder at the bottom, or near the bottom 95 of the well, extends the entire length of the well and just above the surface of the ground it is connected by thread and screw to the collar *J* which is fastened by screw thread connection to the union *K*, which turns as a 100 swivel in the screw threaded union *L*, screwed to the union *M* held to the tube *R* which lat-

ter is held by screw threaded connection to the cap S fastened to the outer gas conveying tube.

The operation of my invention will be readily understood, as when the separator is in place in a well, the lower end rests beneath the surface of the water and oil probably a number of feet, and the valve is opened a suitable distance by turning the collar J, which raises or lowers the inner tube allowing the natural pressure of the gas to force the water and oil into the inner tube and to the surface of the ground, and the gas will be carried outside of the inner tube to the surface, as described.

Having thus described my invention, what I claim to be new, and desire to secure by Letters Patent, is—

In combination the tube B having a cylinder made up of two sections having screw threaded connection and carrying a pivoted valve, the inlet tube E having a flange e telescoping within the said cylinder, the said flange adapted to abut against the inturned end on the lower cylinder section, the gas conveying pipe A, the union K, swiveled to the union L connected to the cap S and carrying the collar J having screw threaded connection with the said inner pipe, substantially as shown and described.

In testimony whereof I affix my signature in presence of two witnesses.

JOHN W. HOUGH.
